UNITED STATES PATENT OFFICE.

JOHN B. O'NEAL, JR., OF WAYCROSS, GEORGIA.

TABLE.

Application filed July 5, 1921. Serial No. 482,413.

To all whom it may concern:

Be it known that I, JOHN B. O'NEAL, Jr., a citizen of the United States, residing at Waycross, in the county of Ware and State 5 of Georgia, have invented a new and useful Table, of which the following is a specification.

This invention has reference to game tables, the primary object of the invention 10 being to provide a table wherein various games may be played thereon, the construction of the table being such as to permit the various game boards to be moved into a position for use, with facility.

15 A further object of the invention is to provide a table of this character having means to receive the various game pieces necessary in the playing of games.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed, may be made within the scope of what is claimed, without departing from the spirit of the invention.

30 Referring to the drawing:—

Figure 1 is a side elevational view of a table constructed in accordance with the present invention.

Figure 2 is a sectional view taken on line 35 2—2 of Figure 1.

Figure 3 is a sectional detail view disclosing the supporting rollers for one of the game boards.

Figure 4 is a sectional view through the 40 web housing and rod on which the web is wound.

Figure 5 is a longitudinal sectional view through the web housing.

Figure 6 is an enlarged fragmental view 45 disclosing the connection between the movable game board and the table.

Referring to the drawings in detail, the reference character 5 designates the end section of the table, which end sections are connected by the horizontal bars 6. End sections 50 5 are also connected by the table top 7 which has cut out portions in the upper surfaces thereof, which cut out portions receive the rollers 8 which have their peripheries extending above the upper surface 55 of the table top 7 to contact with the mov-

able game board 9 to be hereinafter more fully described.

Extending upwardly from each corner of the table top 7 is a block 10, which blocks 60 support the frame 11 that forms the upper portion of the table. The game board 9 is provided with grooves 12, which grooves extend throughout the length of the game board and accommodate the rollers 13 which 65 are mounted on the pivoted arms 14 that have one of their extensions 15 embedded in openings formed in the blocks 10. Thus it will be seen that the game board may be moved from the table the rollers 13 moving 70 along the grooves until the same contact with the end wall of the respective grooves, whereupon the game board may be swung upwardly, to rest the game board on the frame 11. It is to be understood that this 75 game board may be of any particular type, and may be of the combination construction, wherein various games may be played on the board.

Supported under the frame 11 adjacent 80 to each end thereof is a transversely extending housing 16 which is provided with an opening formed along one edge thereof, to permit the web 17 to be pulled through the housing, it being understood that the 85 web is wound on suitable supporting rods 18 mounted within the housing, there being provided operating means on one end of each rod, whereby the rods may be rotated to wind the web thereon.

90 This web may be printed to show maps for educational purposes, or a portion of the web may be blocked off to provide game surfaces such as used in playing checkers, chess or the like. If it is desired to use the game board 9, it is obvious that the same may be pulled outwardly and swung to a 95 position on the frame 11 as before described.

In order that the game pieces employed in connection with the game board may be 100 supported in a convenient location, a drawer 19 is provided.

It might be further stated that suitable fixtures may be attached to the table, such as a lamp indicated at 20 or an ash receiver 105 indicated at 21.

Having thus described the invention, what is claimed as new is:—

A game table comprising end sections, a table top, a game board having grooves 110 formed in the side edges thereof and extending throughout the length of the game

board, arms having pivotal connection with the table and having rollers disposed within the grooves, said rollers adapted to move within the grooves to permit the game board to be withdrawn from the table, and said arms adapted to pivot upwardly to permit the game board to be swung to a position on the table top.

In testimony that I claim the foregoing as my own, I have hereto affixed my signature in the presence of two witnesses.

JOHN B. O'NEAL, JR.

Witnesses:

FRANCES BUFF,
J. P. COLEMAN.
